UNITED STATES PATENT OFFICE.

JOHN SCHOENING, OF KENOSHA, WISCONSIN.

PROTECTOR.

1,137,428.

Specification of Letters Patent. Patented Apr. 27, 1915.

Application filed October 7, 1914. Serial No. 865,539.

To all whom it may concern:

Be it known that I, JOHN SCHOENING, a citizen of the United States, residing at Kenosha, in the county of Kenosha and 5 State of Wisconsin, have invented certain new and useful Improvements in Protectors, of which the following is a specification, reference being had to the accompanying drawings.

10 This invention relates to new and useful improvements in protectors and more particularly to a device adapted to be used in connection with harness, the main object of the present invention being the provision of 15 a protecting device adapted to be used in connection with a collar or a back strap, whereby to protect a sore or irritated surface, upon the animal's body and relieve the same of all contact with the other portion 20 of the harness.

Another object of the present invention is the provision of a protector of the above character which will possess advantages in points of efficiency and durability, is inexpensive to manufacture and, at the same 25 time, is simple in construction and operation.

With the above and other objects in view, the invention consists in the novel features 30 of construction, combination and arrangement of parts as will be hereinafter referred to and more particularly pointed out in the specification and claims.

In the accompanying drawing forming a 35 part of this application, Figure 1 is a side elevation illustrating my improved protector, as used in connection with a horse collar. Fig. 2 is a similar view illustrating the same in use in connection with a back 40 strap. Fig. 3 is a transverse sectional view of the protector itself; and Fig. 4 is a side elevation, parts thereof being illustrated in longitudinal section.

In carrying out my invention, I provide 45 a metallic body plate 1 which is substantially U-shaped in cross section and is provided adjacent each longitudinal edge thereof with the spaced alined slots 2, the purpose of which will be hereinafter more 50 fully set forth. Secured to the outer surface of the body 1, is a plate 3, the ends of which are curved upwardly as shown at 4 to provide stops, adapted to engage the sides of the collar or back band to prevent 55 any sliding movement of the same when the

protector is placed between the body of the animal and the collar or back band. In order to further retain the collar or back band against movement upon the protector, I provide securing straps 5, the inner ends 60 of which are secured to the body 1, upon opposite sides of the center and at one end thereof, and are adapted to engage suitable buckles 6 which are secured by means of the straps 6' to one end of the protector, 65 upon opposite sides of the center. It will be apparent that after the protector has been placed in position upon the animal's body, the collar or back band will then be engaged over the central portion thereof 70 and securely held in position by means of the strap 5 and the curved ends of the plate 3.

Arranged beneath the body 1, is a protecting pad 7, which is of substantially the 75 same shape as the body and formed of any suitable material, such as leather, wool or the like, but preferably of stiff leather, as indicated in the accompanying drawing and is provided at its central portion with an 80 opening 8. It will be further noted that the body of the protecting pad 7 is arranged in spaced relation with the metallic body 1, whereby to provide for an air space between the body 1 and the body of the 85 animal, to which the same is applied so that the irritated surface may be exposed to the air. Secured to the side walls of the pad 7, are the plates 9 which are provided with threaded openings 10 adapted to receive the 90 inner ends of the threaded bolts 11, said bolts being carried by the outer plate 12 and adapted to extend through the slots 2 in the body 1. From this it will be apparent that by loosening the bolts 11, the 95 pad 7 may be adjusted longitudinally with respect to the body 1, without moving the body 1 from its effective position.

From the above description, it will be readily apparent that in the application of 100 my improved protector, the inner pad 7 is placed over the sore or irritated place, so that the opening 8 is arranged directly over the irritated place, whereby none of the parts of the harness or the protector will come in 105 contact with the same and it will be noted that by having the opening 8 therein and by providing a chamber between the pad 7 and the body 1, a thorough circulation of air can pass between the body and the protector so 110

as to come in contact with the irritated portion, whereby it will be more quickly healed than if the usual form of pad were used. It will also be noted that after the protector is placed in position, the pad 7 can be adjusted longitudinally with respect to the body 1, by loosening the screw bolts 11. It will also be apparent from the foregoing description, taken in connection with the accompanying drawing, that I have provided a simple and durable protecting pad for use in connection with strap harness, whereby to protect a sore or irritated place upon an animal's body. It will also be apparent that the portion of the harness to which my pad is applied will be securely fastened to the pad by means of the straps 5 and the buckles 6.

My improved pad, as herein shown and described, is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I claim is:-

1. A device of the class described including a U-shaped metallic body member having alined slots formed adjacent each edge thereof, a protecting pad of substantially the same shape as the body member and adapted to be arranged within the body member and in spaced relation thereto, and means adjustably arranged within said slots

to connect the pad with the body member, as and for the purpose set forth.

2. A device of the class described including a U-shaped metallic body member having alined slots formed therein adjacent each edge, a protecting pad of substantially the same shape as the body member and provided with a central opening, said protecting pad being arranged in spaced relation with the inner walls of the body member to form a chamber between the pad and the body member, plates carried by the side walls of the pad, plates arranged upon the outer side of the metallic body member and screw bolts extended through the slots and engaged with the said plates, whereby said pad may be longitudinally adjusted with respect to the metallic body member, as and for the purpose set forth.

3. A device of the class described including a metallic body member, a protecting pad mounted upon the inner side thereof and in spaced relation therewith, said pad being provided with a central opening communicating with the space between the pad and the body member, plates carried by opposite ends of the pad, screw bolts extended through the slots in the body member and engaged with the plates, whereby said pad may be adjusted longitudinally with respect to the body member, and securing straps carried by the body member, as and for the purpose set forth.

In testimony whereof I hereunto affix my signature in the presence of two witnesses.

JOHN SCHOENING.
